[57] **CLAIM**

The ornamental design for a squirrel-shaped toy or similar article, as shown and described.

DESCRIPTION

FIG. 1 is a front perspective view of a squirrel-shaped toy showing my new design;

FIG. 2 is a front elevation view;

FIG. 3 is a top plan view;

FIG. 4 is a left side view;

FIG. 5 is a right side view;

FIG. 6 is a rear elevation view;

FIG. 7 is a bottom plan view; and

FIG. 8 is a bottom plan view of an alternative embodiment of my squirrel-shaped toy, the other views being shown in FIGS. 1-6.
